UNITED STATES PATENT OFFICE.

MAX C. SHERMAN, OF CYNWYD, AND FRANK B. ALLEN, OF BEN AVON, PENNSYLVANIA, ASSIGNORS TO THE BAKER-DUNBAR-ALLEN COMPANY, OF CLEVELAND, OHIO, A CORPORATION OF OHIO.

ASH-GATE.

1,360,805.

Specification of Letters Patent. Patented Nov. 30, 1920.

Application filed January 8, 1919. Serial No. 270,135.

To all whom it may concern:

Be it known that we, MAX C. SHERMAN, a resident of Cynwyd, in the county of Montgomery and State of Pennsylvania, and 5 FRANK B. ALLEN, a resident of Ben Avon, in the county of Allegheny, State of Pennsylvania, have invented a new and useful Improvement in Ash-Gates, of which the following is a specification.

10 This invention relates to apparatus for handling loose or granular material, and more particularly for storing it and discharging it from time to time. The invention is especially adapted for handling ashes 15 from boiler and like furnaces and in the drawing it is illustrated as adapted for that use.

The object of the invention is to provide 20 means for storing the ashes or other like loose material and for discharging the same from time to time to suitable transporting devices and which discharging means is so arranged as to be easy of operation, to tightly seal the storage hopper or bin, and in which the 25 wearing parts are protected from direct contact with the ashes or like material and therefore not subjected to rapid wear or to clogging.

In the accompanying drawings, Figure 1 30 is a plan view of the lower portion of an ash hopper, together with the gate closing the same and means for operating the gate; Fig. 2 is a vertical longitudinal section taken on the line 2—2; and Fig. 3 is a vertical 35 transverse section taken on the line 3—3, Fig. 1.

The hopper or bin for storing the loose or granular material is indicated at 1, and as 40 illustrated it is a typical form of ash hopper such as used underneath the grates of boiler furnaces in large power plants, the same comprising a suitable metal casing 2, lined with fire brick or other refractory material 3, to protect the metal casing against the 45 heat of the ashes, and which hopper is supported upon suitable beams 4. This hopper at its lower end is provided with a discharge orifice and at said lower end the metal casing is provided with an inwardly projecting 50 flange or ledge 5 for supporting the refractory lining and also with an external flange 6. Underneath the hopper is a casting 7, provided with the discharge opening 8, and at its upper edge horizontal flanges 10 for

securing the casting to the flanges 6 of the 55 hopper casing by means of bolts or the like. This casting at its lower edge is provided with the inwardly projecting flange or ledge 11 for supporting the fire brick or other refractory lining 12, and at the two side 60 edges is provided with outwardly projecting flanges or ledges 13 which form tracks or ways for the gate or valve supporting means hereinafter described. These tracks or ways project beyond the casting at one end, as 65 shown at 14, to allow for the necessary travel of the gate or valve.

The gate or valve comprising a rectangular casting 15, lined with fire brick or other refractory material 16, and provided 70 with laterally projecting suspending arms 17, two at each side of the gate, one near its forward end and the other near its rear end. These arms 17 project underneath and beyond the tracks 13 and have up-turned end 75 portions 18 which are provided with openings for receiving the journal pins 19 of wheels or rollers 20 which travel on the tracks 13 and serve as the means for suspending the gate or valve. Preferably removable and renewable wear strips 21 are provided on the tracks 13 to compensate for any wear which may occur. At both ends of the tracks 13 are upwardly projecting flanges 22, to serve as stops to limit the 85 travel of the gate or valve in both directions, these flanges being shown integral with the casting. To permit assembling of the gate on the tracks or ways, the projecting portions 14 of the casting are provided 90 with holes 23 to permit insertion of the roller journal pins 19.

Connected to one end of the gate or valve, at equal distances from its longitudinal center, are a pair of operating members 24, 95 shown as rods pivotally connected to ears 25 on the gate or valve. These operating rods extend through stationary guides 26 to keep them in alignment and thus overcome any tendency of the gate or valve to become 100 skewed and bind on the tracks or ways from which it is suspended. These operating rods may be connected to any suitable actuating mechanism. As illustrated, the ends of said rods are connected to a crosshead 27, secured 105 to the piston rod 28 of a double acting power cylinder 29, provided with inlets and outlets for the admission and exhaust of any

suitable pressure medium, such as compressed air, to its opposite ends, but as this particular form of actuating mechanism forms no part of the present invention, it is not illustrated or described in detail. Any other suitable mechanism, either power or hand actuated, may be used for reciprocating the gate or valve backwardly and forwardly.

- 10 The tracks or ways 13 are at a slight angle to the bottom face of the casting surrounding the discharge opening 8, and the inclination is such that when the gate is moved to position to close the discharge opening 8, it wedges against the lower face of the casting surrounding said opening, thus tightly sealing said opening, but when the gate is drawn in the direction to open the discharge opening it clears the lower face of the casting surrounding the discharge opening, and therefore can be easily and freely moved. The amount of the inclination of the tracks or ways relative to the bottom face of the casting surrounding the discharge opening is very slight, from $\frac{1}{8}$ " to $\frac{1}{4}$ " in a full sized apparatus, and is therefore not noticeable on the drawings of the scale of those hereto annexed.

Preferably the rear edge of the gate or valve is provided with an edge portion, preferably somewhat sharp as shown at 30, which serves to shear or break off any clinker which may stick in the discharge opening, upon the backward or closing movement of the gate.

It will be observed that the tracks or ways from which the gate or valve is suspended are located externally of the discharge opening, and consequently the ashes or other loose material discharged from the hopper cannot get on to said tracks or ways. As a consequence, the tracks or ways remain clean and are not subjected to wear nor can the rollers or wheels become clogged thereon as is the case where the tracks or ways project inwardly and are therefore subjected to the wearing and clogging action of the ashes or other gritty material. It will also be observed that the flanges 10 at the upper edge of the casting 7 project laterally above the tracks or ways, so that external dirt or gritty matter cannot fall upon the said tracks. In these ways the tracks are protected against clogging and excessive wear, so that positive closure and a tight sealing of the discharge opening can be secured. Furthermore, the rollers or wheels are at all times accessible from the outside for inspection, oiling and repairing.

60 The operation of the apparatus will be readily understood. By means of the power cylinder 29, or other suitable means, the gate can be reciprocated in either direction.

When moved to the position shown in Fig. 2, it tightly closes the discharge opening, and when moved toward the left, viewing Fig. 2, the ashes or other material in the hopper 1 will discharge by gravity through the discharge opening 8. If clinker lodges in the discharge opening it can be broken and dislodged by forcibly striking the same with the rear edge of the gate.

We claim:

1. In combination with a hopper provided with a bottom discharge opening, of a frame surrounding said opening and provided on opposite sides thereof with a pair of outwardly extending flanges spaced vertically of each other, a horizontally movable gate provided with suspending means extending laterally and upwardly and engaging over the lower one of said flanges and being overhung by the upper one thereof, and means for reciprocating said gate.

2. In combination with a hopper provided with a bottom discharge opening, of a frame surrounding said opening, and provided on opposite sides thereof with a pair of outwardly extending flanges spaced vertically of each other, a horizontally movable gate provided with lateral projections having upturned end portions, and rollers secured to said up-turned portions and running on the lower one of said flanges and being overhung by the upper one thereof.

3. An apparatus of the character described, in combination with a hopper having a bottom discharge opening, of a frame surrounding said discharge opening and provided with inturned flanges and on opposite sides with externally projecting flanges, said external flanges projecting beyond one end of said casting, refractory material supported on the inwardly projecting flanges of said casting, a gate provided with laterally extending means engaging the outwardly projecting flanges on said casting and suspending the gate therefrom, and means for reciprocating said gate.

4. In combination with a hopper provided with a bottom discharge opening, of a metal frame surrounding said hopper and provided at its bottom face with inwardly projecting flanges, refractory material supported by said flanges, a horizontal movable gate mounted to reciprocate underneath said frame, said gate being covered with refractory material and provided with a rear breaking edge flush with its top surface, and mechanism for reciprocating said gate.

In testimony whereof, we have hereunto set our hands.

MAX C. SHERMAN.
F. B. ALLEN.
